US00D810720S

(12) **United States Design Patent** (10) **Patent No.:** **US D810,720 S**
(45) **Date of Patent:** **** Feb. 20, 2018**

(54) **EARPHONE**

(71) Applicant: **Cirque Audio Technology Co., Ltd.**,
Dongguan (CN)

(72) Inventor: **Mark Lee**, Dongguan (CN)

(73) Assignee: **CIRQUE AUDIO TECHNOLOGY
CO., LTD.**, Dongguan (CN)

(**) Term: **15 Years**

(21) Appl. No.: **29/589,272**

(22) Filed: **Dec. 29, 2016**

(30) **Foreign Application Priority Data**

Dec. 14, 2016 (CN) 2016 3 0614777

(51) **LOC (11) Cl.** **14-01**
(52) **U.S. Cl.**

USPC **D14/205**

(58) **Field of Classification Search**

USPC D14/205, 223, 218; 181/129, 130, 135;
379/430, 431; 381/380, 381, 74, 370;
455/90.3, 575.1, 569.1

CPC H04R 1/10; H04R 1/1041; H04R 1/105;
H04R 1/1091; H04R 1/1016; H04R
5/033; H04R 5/0335; H04R 1/1033

See application file for complete search history.

Primary Examiner — Paula Allen Greene

(74) *Attorney, Agent, or Firm* — Ming Chow; Sinorica,
LLC

(57) **CLAIM**

The ornamental design for an earphone, as shown and described.

DESCRIPTION

FIG. 1 is a front elevation view thereof;
FIG. 2 is a rear elevation view thereof;
FIG. 3 is left side view thereof;
FIG. 4 is right side view thereof;
FIG. 5 is a top plan view thereof; and,
FIG. 6 is a bottom plan view thereof.

1 Claim, 6 Drawing Sheets
